UNITED STATES PATENT OFFICE.

PHILIP A. FUCHS, OF MILWAUKEE, WISCONSIN.

PULLEY-SUPPORTING BRACE.

1,301,830.

Specification of Letters Patent. Patented Apr. 29, 1919.

Application filed April 2, 1917. Serial No. 159,181.

To all whom it may concern:

Be it known that I, PHILIP A. FUCHS, a citizen of the United States, residing at Milwaukee, county of Milwaukee and State 5 of Wisconsin, have invented new and useful Improvements in Pulley-Supporting Braces, of which the following is a specification.

My invention relates to improvements in pulley supporting braces for tube systems.

10 The object of my invention is to provide removable means for supporting a pulley near the bottom of a catch basin or man hole pit of a sewerage system or any other system of pipes or tubes in which it is desirable to draw cleaning apparatus through 15 the pipes or tubes at intervals. My invention makes it possible to support a pulley in such a position that a cable may be drawn through the sewer or horizontal pipe 20 and passed around the pulley and upwardly to the exterior through a man hole or catch basin, whereby cleaning apparatus having another cable and a hose attached thereto may be guided into the sewer from another 25 catch basin or man hole as the cleaning apparatus advances, the apparatus being advanced or retracted by means of the cables and the hose being used to deliver water to the apparatus for power or flushing purposes.

30 The drawing illustrates my improved apparatus in elevation as located for use within a sewer system, fragments of the sewer pipes and of a pair of man holes or 35 catch basins being illustrated in vertical section.

In the drawings, each man hole or catch basin communicates at the bottom with pipe sections 2, 3 and 4 respectively. My improved brace is formed in telescoping sections 5 and 6, the lower section 5 being 40 pivotally connected at 7 with a shoe 8 adapted to rest upon the bottom of the sewer. The lower section 5 is also provided with a bracket 9 in which a hook arm 45 10 may engage, this arm having swivel connection with a pulley block 11 in which a pulley 12 is journaled. The bracket 9 is preferably in the form of a staple, the two 50 legs being passed through apertures in the section 5 of the brace near its lower end and threaded to receive the nuts 13.

The upper section 6 of the brace is provided with a series of apertures 14 adapted 55 to receive a pin or bolt 15 which extends through a bolt receiving aperture in the

upper end of section 5. In the drawing, this connection is illustrated as a bolt 15 threaded to receive a nut 16, whereby the sections 5 and 6 of the brace may be securely locked together. The upper end of the brace section 6 is flattened as illustrated at 17 and provided with a wedge shaped extremity adapted to engage against or between the bricks or blocks forming the wall 60 of the man hole or catch basin.

By forming the brace in adjustable sections, it is possible to utilize it in catch basins or man holes which differ in diameter. The sections are of such length that 70 the braces may be readily manipulated to the position in which they are illustrated in the drawings. The shoe 8 may be pushed into one of the sewer pipes for a short distance, with section 5 of the brace extending 75 upwardly therefrom in an inclined position. The section 6 of the brace may be extended in correspondence with the diameter of the catch basin or man hole and it may either be extended after the shoe 8 has been placed 80 in position as illustrated in the drawing, or if desired, the section 6 may be adjusted to the proper position before inserting the brace. In either case, the section 6 will be extended sufficiently to support the brace 85 in an inclined position with its upper end in anchorage engagement with the wall of the catch basin or man hole.

The pulley 11 is supported by the brace in a position to receive an actuating cable 90 20 which cable extends from the cleaning apparatus 21 through the sewer pipe 3, around the pulley and vertically through the man hole 1. The pulley is adapted to receive the cable in such a position that 95 when the latter is drawn upwardly the force exerted upon the pulley will not only increase the pressure of the wedge shaped upper extremity against the wall of the basin, but owing to the proximity of the 100 pulley to the lower end of the section 5, the shoe will be drawn forcibly downward into contact with the bottom of the sewer, due to the resultant force exerted on the pulley. The apparatus may be retracted by a re- 105 tracting cable 22 extending to the rearward catch basin or man hole.

It will be observed that the cables are operated by means of windlasses 23 located above the respective man holes. Only one 110 brace is required, when the apparatus is being advanced, viz: that at the man hole

in front of the machine (shown at the left in the drawing). But where the apparatus is to be retracted, a similar brace will be used in the other man hole. The hose pipe 5 24 may be coupled at intervals to the retracting cable 22, whereby the cable may be utilized to withdraw the hose. In such case, the hose will be uncoupled from the cable as it reaches the exit, thus allowing 10 the cable to pass around the pulley.

I claim:

The combination with a sewer cleaner, of a cable for drawing the same through the sewer, a pulley supporting brace adapted to 15 extend obliquely from the bottom of the sewer adjacent to the man-hole, across the man-hole into contact with its opposing wall, a pulley connected with the brace in a position to be supported thereby near the

lower end thereof and adjacent to one wall 20 of the man-hole, said cable being extended around said pulley and upwardly through the man-hole and adapted to draw the upper end of the brace against the opposing wall, and the lower end of the brace against 25 the bottom of the sewer, said brace having a pivoted foot piece at its lower end, and an extensible section at its upper end terminating in a wedge shaped extremity adapted for biting anchorage in the wall of 30 the man-hole.

In testimony whereof I affix my signature in the presence of two witnesses.

PHILIP A. FUCHS.
